(57) **CLAIM**

I claim the ornamental design for a LED nail dryer lamp, as shown and described.

DESCRIPTION

FIG. 1 is a rear perspective view of the preferred embodiment.

FIG. 2 is a top plan view of the preferred embodiment.

FIG. 3 is a front view of the preferred embodiment.

FIG. 4 is a rear view of the preferred embodiment.

FIG. 5 is a left side elevation view of the preferred embodiment; and,

FIG. 6 is the right side elevation view of the preferred embodiment.

Portions of the LED nail dryer lamp are shown in broken lines for illustration purposes only, and form no part of the claimed design.
